UNITED STATES PATENT OFFICE.

WILLIAM WEBSTER, OF LONDON, ONTARIO, CANADA, ASSIGNOR, BY MESNE ASSIGNMENTS, TO THE WARREN FEATHERBONE COMPANY OF MICHIGAN, OF THREE OAKS, MICHIGAN, A CORPORATION OF MICHIGAN.

MACHINE FOR PREPARING STIFFENING MATERIALS.

No. 926,790.

Specification of Letters Patent.

Patented July 6, 1909.

Application filed April 24, 1902. Serial No. 104,573.

To all whom it may concern:

Be it known that I, WILLIAM WEBSTER, a citizen of the United States, residing at the city of London, in the county of Middlesex, 5 Province of Ontario, Canada, have invented certain new and useful Improvements in Machines for Preparing Stiffening Materials, of which the following is a specification.

This invention relates to improved means 10 for assembling fibers such as the fiber and quill or enamel portion of feathers into cords. Heretofore, this has been accomplished by feeding the fibers by hand to a winding machine. This entails a great amount of labor 15 and requires some skill on the part of the operator, to produce a perfectly even and satisfactory cord.

The object of this invention is to provide a machine which shall automatically feed the 20 fibers into a suitable winding machine which delivers the same properly wound or assembled into a cord.

Further objects of the invention are to provide an efficient feeding device and an efficient 25 automatic stop for such a machine, which shall act whenever the machine becomes out of order or the supply of fibers fails, or the winding thread breaks, and to provide an improved arrangement of gears 30 for the actuation of such a machine.

Further objects and objects relating to structural details, will definitely appear from the detailed description to follow.

I accomplish the objects of my invention 35 by the devices and means described in the following specification.

The invention is clearly defined and pointed out in the claims.

A structure embodying the features of my 40 invention is clearly illustrated in the accompanying drawing, forming a part of this specification, in which—

Figure 1 is a plan view of a structure embodying the features of my invention. Fig. 45 2 is a vertical longitudinal sectional view taken on line 2—2 of Fig. 1. Fig. 3 is a transverse detail sectional elevation view taken on lines 3—3 of Figs. 1 and 2. Fig. 4 is a detail longitudinal sectional elevation 50 view of the feed mechanism for the fiber, taken on a line corresponding to line 4—4 of Fig. 3. Fig. 5 is an enlarged detail trans-

verse sectional elevation view of the feed mechanism taken on line 5—5 of Fig. 1. Fig. 6 is a transverse detail sectional view of 55 the delivery rolls for taking the cord from the machine, taken on a line corresponding to line 6—6 of Fig. 1, showing details of construction. Fig. 7 is an enlarged detail sectional view taken on a line corresponding to 60 line 7—7 of Fig. 1, showing the arrangement of the tight and loose pulleys E E'. Fig. 8 is an enlarged detail elevation view of the packer finger for the fiber feeding device. Fig. 9 is a detail transverse sectional view 65 taken on a line corresponding to line 9—9 of Fig. 2 showing details of the automatic stop mechanism. Fig. 10 is an enlarged detail longitudinal view of the automatic stop mechanism taken on a line corresponding to 70 line 10—10 of Fig. 9.

In the drawing, the sectional views are taken looking in the direction of the little arrows at the ends of the section lines, and similar letters of reference refer to similar 75 parts throughout the several views.

Referring to the lettered parts of the drawing, A is the base supporting the remaining parts of the machine, which, in this instance, is shaped somewhat like the letter L, having 80 a main longitudinal portion and a lateral portion. On the lateral portion is a bracket A' which serves as a support for the shaft L, which carries the driving mechanism for the machine consisting of a tight and a loose 85 pulley, E E'. The driving or tight pulley E is supported on a sleeve which is rotatably mounted on the end of the stub shaft L and the loose pulley E' is supported on the sleeve-like hub of the pulley E and is retained in 90 position by a tight-fitting collar E''. The stub shaft L is supported in the bracket A by a suitable set screw z.

On the main portion of the frame are brackets I I' and B which carry the essential parts 95 of the machine. On the bracket I is supported a hopper J which is made substantially V-shaped at the bottom with parallel upwardly-extending walls. A vertical slot is cut in the walls of this hopper J to receive the 100 staple-like holder J'. The holder J' embraces the fibers M in the hopper and forces them toward the bottom thereof, retaining them parallel and under a slight pressure to

- insure their proper delivery. At the delivery end of the hopper, and projecting into the same slightly, are feed rolls i i' . These feed rolls are adapted to engage some of the lower fibers at their front ends and carry them toward the winder. The feed rolls i i' are geared together and have engaging surfaces projecting above the gears, see Figs. 2, 3, and 5—the roll i driving the roll i' , see Fig. 5.
- 10 The roll i is supported on a shaft g having a bevel gear g' on its lower end. This gear g' meshes with gear h on the shaft H which is driven from the opposite end of the machine.
- 15 The roll i' is carried on an adjustable block j , held normally toward the roll i by a spring f' —which is preferably a coiled spring. The tension of the spring is adjusted by means of a thumb screw f'' , so that the rolls are held into yielding contact with each other.
- 20 A packer or feed finger n' is arranged through a vertical slot in the side of the hopper J . An arm n is pivoted at t on a suitable boss on the bracket I . The finger n' is pivoted on the arm n , and rests against the stop m' thereon. The finger n is held yieldingly against the stop by a spring m —see Fig. 8.
- 25 Connected to the arm n is a pitman o which is connected by a suitable wrist pin to the disk o' on the end of the shaft H , so that with every rotation of the shaft H , a quantity of the fibers is fed down between the feed rolls i i' , and such quantity will be carried forward.
- 30 A funnel-like feed or delivery trough K is arranged to the rear of the feed rolls i i' and the fibers are delivered rearwardly through the same in sufficient quantity to form a cord of the desired size.
- 35 A funnel-like feed or delivery trough K is arranged to the rear of the feed rolls i i' and the fibers are delivered rearwardly through the same in sufficient quantity to form a cord of the desired size.
- 40 The winding mechanism for winding the fibers with thread consists in part of a fixed tubular spindle D which carries the spool v . The spool v is mounted on the cones v' v'' carried by the spindle. The cone v'' is adjustably secured to the spindle by means of a set screw. The cone v'' is yieldingly supported by the spring v''' (see Figs. 1 and 2). By adjusting this cone v'' the running friction on the spool is adjusted thereby adjusting the tension on the winding thread.
- 45 A guide is provided for the thread, consisting of a tubular winding arm F supported on the revolving disk C' . This arm extends forwardly past the spool to the proper point for delivering the thread onto the strand of fibers. The end of the arm is notched to retain the thread thereon. Within this tube F is a small plunger F' held normally toward the rear by a coiled spring e' . On this plunger is the hook e which projects through a longitudinal slot in the arm. The thread u engages this hook in passing over the guide to the strand of fibers. The tension on this thread is sufficient to draw the plunger normally forward to about the position indi-

cated in Figs. 1 and 10. When the thread u for any reason slackens or becomes broken, this plunger F' is thrown backward by the force of the spring e' and projects out from the end of the tube F beyond the face of the disk C' , and actuates the lever G . The lever G is connected to a belt shipper. With the parts arranged as described, when the spool is emptied, or the thread broken, or the supply of fibers fails, the machine is thrown out of gear automatically.

The machine is driven from the pulley E at the side of which is a loose pulley E' . The power is delivered by a belt P . A shipper arm r is pivoted to a suitable bracket on the base A . The arm r has a downwardly extending arm r' . A spring s is provided for actuating the belt shipper when it is released. When the machine is in operation the arm r' is engaged by the latch l on the rock shaft G' . On the rock shaft G' is an arm G , which extends upwardly into proximity with the rear face of the disk C' . When the plunger F' projects beyond the rear face of the disk, it strikes this lever G which trips the latch l and permits the spring s to ship the belt to the loose pulley, thus stopping the machine. Stops p and p' are provided for the arm r' . Suitable stops not here illustrated are provided for the rockshaft G' .

95 The pulley E is flat faced, and is provided with a spiral thread or rib a'' . This thread engages and drives the delivery roll a' which, coöperating with its companion roll a , delivers the cord from the machine.

On the rear end of the shaft H is a gear wheel H' which is also driven by the spiral thread or rib on the pulley E . Thus connected, the feed rolls i i' and the delivery rolls a a' are driven at the same rate of speed. The pulley E is driven by the belt P .

100 The delivery rolls a a' are supported on the bracket B , the roll a being yieldingly supported on a block b and held yieldingly in position by the coiled spring b' . A thumb screw b'' is provided for adjusting the tension of the spring.

105 A bracket B' is supported on the bracket B by a screw c which permits it being swung and adjusted back and forth. The set screw d carried in a suitable projection on the bracket B is provided for adjusting this bracket.

110 The spindle D is held in this bracket B' , by means of a suitable set screw. The sleeve D' is revolvably supported on this tube and the friction pulley C is suitably secured to the sleeve D' , and is driven by contacting with the face of the pulley E .

115 On the front end of the sleeve D' is the disk C' which carries the arm F , along which the winding thread is guided and by means of which it is delivered onto the strand of fiber M' .

120 Having thus described the various parts of

my improved machine, I will now briefly indicate their operation. A spool *v* of the thread is placed on the spindle and a quantity of fibers *M*, arranged parallel with each other, are placed in the hopper *J*, and the holder *J'* is placed over the same to carry them downward to the bottom of the hopper. The machine is then set in motion. The arm *n* begins to oscillate up and down, and the finger *n'* engages a small definite quantity of fibers and forces them down to the bottom of the hopper *J* where they are engaged by the feed rolls *i i'* and carried into the trough *K*, which is positioned to deliver them into the tubular spindle. At this point, the wrapping thread *u* is wrapped onto the same by the winder and the strand is drawn on through the tubular spindle to the rear end of the machine by the delivery rolls *a a'*. This operation continues as long as there is a supply of fibers and the thread *u* remains intact. Should the thread *u* become broken, the plunger *F'* will be thrown to the rear and will actuate the lever *G* which will release the belt shipper and stop the machine. The same thing occurs if the thread *u* becomes slack from any reason, and the same thing will occur if the supply of fibers fails, so that the machine is automatically stopped when the supply of either fibers or thread is exhausted or an accident to the fiber feeding mechanism occurs.

I have shown a simple arrangement for driving. It is what I consider to possess merit over any other, but I desire to remark that a variety of connections could be made for driving the different parts, what I have shown being a very simple connection for the various parts.

In the winder, I have shown, the spool is relatively stationary the thread being taken off from the same, which is the most perfect form of winder, but I am aware that there are other means by which the spools might revolve without changes in the structure; but I would not be understood as restricting my claims to the particular form of winder. I wish it understood that I desire to claim the same both broadly and specifically.

Having thus described my invention, what I claim as new and desire to secure by Letters-Patent, is—

1. In a machine for automatically feeding and winding fibers into strands, the combination of a suitable base; a feed mechanism consisting of a hopper *J* having a **V**-shaped bottom, a staple-like holder *J'* adapted to embrace the fibers and carry them down in the hopper, a pair of feed rolls *i i'* arranged below said hopper toward the front thereof adapted to engage the bottom fibers therein, means for adjusting said rolls, and an arm *n* carrying a yielding finger *n'* at its inner end, adapted to engage the fiber in said hopper, connections for oscillating said arm whereby

a predetermined quantity of fiber is delivered to said feed rolls and a trough *K* arranged to receive the fiber from said feed rolls; a winding mechanism consisting of a tubular spindle *D* adapted to receive the fiber from said trough *K* and having a thread spool revolvably supported thereon, a sleeve *D'* adapted to revolve on said spindle *D*, and a tubular winding arm *F* carried on said sleeve adapted to deliver thread to said fiber as it is delivered from said trough *K*; a plunger *F'* within said winding arm having a projecting hook *e* for engaging the thread, a tension spring for said plunger, a belt shipper, a spring for actuating the same, a catch for retaining the said belt shipper in its driving position, a lever adapted to release said catch arranged to be actuated by said plunger when the same is released by said thread, and a pair of delivery rolls *a a'*, all coacting for the purpose specified.

2. In a machine for automatically feeding and winding fibers into strands, the combination of a suitable base, a feed mechanism consisting of a hopper *J* having a **V**-shaped bottom, a pair of feed rolls *i i'* arranged below said hopper toward the front thereof adapted to engage the bottom fibers therein, an arm *n* carrying a yielding finger *n'* at its inner end adapted to engage the fiber in said hopper, connections for oscillating said arm whereby a predetermined quantity of fiber is delivered to said feed rolls and a trough *K* arranged to receive the fiber from said feed rolls; a winding mechanism consisting of a tubular spindle *D* adapted to receive the fiber from said trough *K* and having a thread spool revolvably supported thereon, a sleeve *D'* adapted to revolve on said spindle *D* and a tubular winding arm *F* carried on said sleeve adapted to deliver thread to said fiber as it is delivered from said trough *K*; a plunger *F'* within said winding arm having a projecting hook *e* for engaging the thread, a tension spring for said plunger, a belt shipper, a spring for actuating the same, a catch for retaining the said belt shipper in its driving position, a lever adapted to release said catch arranged to be actuated by said plunger when the same is released by said thread and a pair of delivery rolls *a a'*, all coacting as described and for the purpose specified.

3. In a machine for automatically feeding and winding fibers into strands, the combination of a suitable base; a feeding mechanism consisting of a hopper *J* having a **V**-shaped bottom, a pair of feed rolls *i i'* arranged below said hopper toward the front thereof adapted to engage the bottom fibers therein, an arm *n* carrying a yielding finger *n'* at its inner end adapted to engage the fiber in said hopper, connections for oscillating said arm whereby a predetermined quantity of fiber is delivered to said feed rolls and a trough *K* arranged to receive the fiber from

said feed rolls; a winding mechanism consisting of a tubular spindle D adapted to receive the fiber from said trough K and having a thread spool revolubly supported thereon, a sleeve D' adapted to revolve on said spindle D and a tubular winding arm F carried on said sleeve adapted to deliver thread to said fiber as it is delivered from said trough K; a plunger F' within said winding arm having a projecting hook e for engaging the thread, a tension spring for said plunger, a belt shipper, a spring for actuating the same, a catch for retaining the said belt shipper in its driving position and a lever adapted to release said catch arranged to be actuated by said plunger when the same is released by said thread, all coacting substantially as described and for the purpose specified.

4. In a machine for automatically feeding and winding fibers into strands, the combination of a suitable base; a feed mechanism consisting of a hopper J having a V-shaped bottom, a pair of feed rolls i i' arranged below said hopper toward the front thereof, adapted to engage the bottom fibers therein, an arm n carrying a yielding finger n' at its inner end adapted to engage the fibers in said hopper, connections for oscillating said arm, whereby a predetermined quantity of fiber is delivered to said feed rolls and a trough K arranged to receive the fiber from said feed rolls; a winding mechanism consisting of a tubular spindle D adapted to receive the fiber from said trough and having a thread spool revolubly supported thereon, a sleeve D' adapted to revolve on said spindle D and a winding arm carried on said sleeve adapted to deliver thread to said fiber as it is delivered from said trough K, all coacting substantially as described and for the purpose specified.

5. In a machine for automatically feeding and winding fibers into strands, the combination of a suitable base; a feed mechanism consisting of a hopper J having a V-shaped bottom, a staple-like holder J' adapted to embrace the fibers and carry them down in the hopper, a pair of feed rolls i i' arranged below said hopper toward the front thereof adapted to engage the bottom fibers therein and a trough K arranged to receive the fiber from said feed rolls; a winding mechanism consisting of a tubular spindle D adapted to receive the fiber from said trough K and having a thread spool revolubly supported thereon, a sleeve D' adapted to revolve on said spindle D and a tubular winding arm F carried on said sleeve adapted to deliver thread to said fiber as it is delivered from said trough K; a plunger F' within said winding arm having a projecting hook e for engaging the thread, a tension spring for said plunger, a belt shipper, a spring for actuating the same, a catch for retaining the said belt shipper in its driving position, a lever

adapted to release said catch arranged to be actuated by said plunger when the same is released by said thread and a pair of delivery rolls a a', all coacting substantially as described and for the purpose specified.

6. In a machine for automatically feeding and winding fibers into strands, the combination of a suitable base; a feed mechanism consisting of a hopper J having a V-shaped bottom, a pair of feed rolls i i' arranged below said hopper toward the front thereof adapted to engage the bottom fibers therein and a trough K arranged to receive the fiber from said feed rolls; a winding mechanism consisting of a tubular spindle D adapted to receive the fiber from said trough K and having a thread spool revolubly supported thereon, a sleeve D' adapted to revolve on said spindle D and a tubular winding arm F carried on said sleeve adapted to deliver thread to said fiber as it is delivered from said trough K; a plunger F' within said winding arm having a projecting hook e for engaging the thread, a tension spring for said plunger, a belt shipper, a spring for actuating the same, a catch for retaining the said belt shipper in its driving position and a lever adapted to release said catch arranged to be actuated by said plunger when the same is released by said thread, all coacting substantially as described and for the purpose specified.

7. In a machine for automatically feeding and winding fibers into strands, the combination of a suitable base; a feed mechanism consisting of a hopper J having a V-shaped bottom, a pair of feed rolls i i' arranged below said hopper toward the front thereof adapted to engage the bottom fibers therein and a trough K arranged to receive the fiber from said feed rolls; and a winding mechanism consisting of a tubular spindle D adapted to receive the fiber from said trough K and having a thread spool revolubly supported thereon, a sleeve D' adapted to revolve on said spindle D and a winding arm carried on said sleeve adapted to deliver thread to said fiber as it is delivered from said trough K, all coacting substantially as described and for the purpose specified.

8. In a machine for automatically feeding and winding fibers into strands, the combination of a suitable base; a feed mechanism consisting of a hopper J having a V-shaped bottom, a staple-like holder J' adapted to embrace the fibers and carry them down in the hopper, a pair of feed rolls held yieldingly toward each other arranged below said hopper toward the front thereof adapted to engage the bottom fibers therein, an arm n carrying a yielding finger n' at its inner end adapted to engage the fibers in said hopper and deliver them to the feed rolls and a funnel-like trough adapted to receive said fibers from said rolls; and a winding mechan-

ism adapted to wind said fibers as they are delivered from said trough, all coacting for the purpose specified.

9. In a machine for automatically feeding and winding fibers into strands, the combination of a suitable base; a feed mechanism consisting of a hopper *J* having a **V**-shaped bottom, a pair of feed rolls held yieldingly toward each other arranged below said hopper toward the front thereof adapted to engage the bottom fibers therein, an arm *n* carrying a yielding finger *n'* at its inner end adapted to engage the fibers in said hopper and deliver them to the feed rolls and a funnel-like trough adapted to receive said fibers from said rolls; and a winding mechanism adapted to wind said fibers as they are delivered from said trough, all coacting for the purpose specified.

10. 10. In a machine for automatically feeding and winding fibers into strands, the combination of a suitable base; a feed mechanism consisting of a hopper having a **V**-shaped bottom, a staple-like holder adapted to embrace the fibers and carry them down in the hopper, a pair of feed rolls held yieldingly toward each other arranged below said hopper toward the front thereof, adapted to engage the bottom fibers therein and an arm *n* carrying a yielding finger *n'* at its inner end adapted to engage the fibers in said hopper and deliver them to the feed rolls; and a winding mechanism adapted to wind said fibers as they are delivered by said feed rolls, all coacting for the purpose specified.

11. In a machine for automatically feeding and winding fibers into strands, the combination of a suitable base; a feed mechanism consisting of a hopper having a **V**-shaped bottom, a pair of feed rolls held yieldingly toward each other arranged below said hopper toward the front thereof, adapted to engage the bottom fibers therein and an arm *n* carrying a yielding finger *n'* at its inner end adapted to engage the fibers in said hopper and deliver them to the feed rolls; and a winding mechanism adapted to wind said fibers as they are delivered by said feed rolls, all coacting for the purpose specified.

12. In a machine for automatically feeding and winding fibers into strands, the combination of a suitable base; a feed mechanism consisting of a hopper having a **V**-shaped bottom, a staple-like holder adapted to embrace the fibers and carry them down in the hopper, a pair of feed rolls held yieldingly toward each other arranged below said hopper toward the front thereof, adapted to engage the bottom fibers therein and a funnel-like trough adapted to receive said fibers from said rolls; and a winding mechanism adapted to wind said fibers as they are delivered from said trough, coacting for the purpose specified.

13. In a machine for automatically feed-

ing and winding fibers into strands, the combination of a suitable base; a feed mechanism consisting of a hopper having a **V**-shaped bottom, a staple-like holder adapted to embrace the fibers and carry them down in the hopper, and a pair of feed rolls held yieldingly toward each other arranged below said hopper toward the front thereof, adapted to engage the bottom fibers therein; and a winding mechanism adapted to wind said fibers as they are delivered by said feed rolls, coacting for the purpose specified.

14. In a machine for automatically feeding and winding fibers into strands, the combination of a suitable base; a feeding device for the fiber consisting of a hopper and a pair of feed rolls adapted to engage the fibers at the bottom of said hopper; a winding mechanism; a plunger controlled by the winding mechanism; a belt shipper mechanism, and a catch for the belt shipper mechanism in position to be released by said plunger, all coacting for the purpose specified.

15. In a machine for automatically feeding and winding stiff fibers into strands, the combination of a suitable base; a feeding device for the fiber, consisting of a **V**-shaped hopper and a pair of feed rolls provided with reduced portions at their upper edge, said reduced portions coacting to form a fiber receiving notch whereby the fibers in the bottom of the hopper are engaged and fed forward as the rolls revolve, and a trough into which said fibers are fed by said feed-rolls, said trough having a mouth adapted to hold said fibers in an assembled condition; and a winding mechanism arranged to wind said fibers as they are delivered from the mouth of said trough, into a continuous strand; and a pair of delivery rolls arranged at the rear of said winding mechanism.

16. In a machine for automatically feeding and winding stiff fibers into strands, the combination of a suitable base; a feeding device for the fiber, consisting of a **V**-shaped hopper and a pair of feed rolls provided with reduced portions at their upper edge, said reduced portions coacting to form a fiber receiving notch whereby the fibers in the bottom of the hopper are engaged and fed forward as the rolls revolve, and a trough into which said fibers are fed by said feed-rolls, said trough having a mouth adapted to hold said fibers in an assembled condition; and a winding mechanism arranged to wind said fibers as they are delivered from the mouth of said trough, into a continuous strand.

In witness whereof, I have hereunto set my hand and seal in the presence of two witnesses.

WILLIAM WEBSTER. [L. S.]
